Attorney.

UNITED STATES PATENT OFFICE.

POWEL CROSLEY, JR., OF CINCINNATI, OHIO.

RHEOSTAT.

Application filed November 3, 1923. Serial No. 672,492.

My invention relates to rheostats, and more particularly to those for use in circuits of low voltage, as in radio receiving apparatus or any other apparatus where a large number of relatively small variations of resistance are required, to afford appreciable variation of current with such low voltage.

The object of my invention is to provide a simple, compact and inexpensive rheostat, easy to install, especially under the conditions encountered in supplying parts of apparatus to various users who assemble them variously to suit their own purposes. A further object is to provide, in one simple apparatus, for increasing resistance at a relatively slow rate, and also for increasing resistance at a relatively rapid rate, to make the device suitable for regulating the operation of apparatus, such as the vacuum tubes of radio apparatus, of different makes. Another object, preferably, is to insure durability against mechanical wear and heating as well as other electrical effects. Other objects will appear in the course of the ensuing description.

I attain these objects by the device illustrated, for example, in the accompanying drawing, in which—

Figure 1 is a rear or inside elevation, parts 30 of the support and connections being shown, and the rheostat being adjusted to a point about half way of its range of adjustment;

Fig. 2 is an upright section on the plane of the broken line 2—2 of Fig. 1;

Fig. 3 is an enlarged fragmentary view, with the pitch of the coils exaggerated, to illustrate the connection of two sections of the coil;

Fig. 4 is a detail perspective view of the radial connector; and

Fig. 5 is a similar view of the central spring.

The core 1 is curved into an almost complete circle with ends almost meeting, and its cross-section is that of a flat rectangle with its lesser dimension radial to the curving, presenting one broad side inward. Its surface is insulating, and preferably it is entirely of insulating material, such as hard rubber, fiber, or other composition readily bent into the annular form described.

Around this core 1 is wound the resistance wire 2 of relatively low specific resistance, and the resistance wire 3 of relatively high specific resistance, both preferably of the same cross-section; the differences in specific

resistance being utilized to afford a greater increase in resistance per turn of wire in the second wire 3 than in the first wire 2, and both wires being wound uniformly, in spaced turns, usually a little farther apart than the diameter of the wire.

The free end of the second wire 3 is passed through a hole in the core 1 some distance from one end of the core and is clinched or otherwise suitably secured, without electrical connection to any other conductor; and the opposite end of the first wire 2 is passed through a hole about the same distance from the opposite end of the core 1, from the outer to the inner side, and has its end clamped under the head of the terminal screw 4 passing out through the core near this end.

The mounting is a shallow cup 5 with insulating surface and preferably made entirely of insulating material, such as porcelain, hard rubber, fiber or the like; and the core 1 with its wires 2 and 3 wound thereon, fits snugly in this cup. The opposite end of the core 1 has the other terminal screw 6 passing out through it; and the rim of the cup 5 has recesses 7 receiving these screws 4 and 6, which have nuts 8 on their respective outer parts, clamping tightly against the outside of the cup and thus holding the core and its windings in the cup.

Additional nuts 9 on the screws 4 and 6 clamp suitable connectors 10 against the nuts 8; it being understood that any desired conductors may be attached to these connectors for including the rheostat in a circuit.

The shaft 11 passes centrally through the cup 5 and through the panel 12 on which the cup 5 is mounted by means of a flat-headed screw 13 passed in through the panel and cup, with a nut 14 against the inner side of the cup. Fixed on the outer end of the shaft 11 is the knob 15. Inside, the radial connector 16 has a circular end part 17 with a central opening through which the shaft 11 extends, and a foot 18 with an opening through which the second terminal screw 6 passes, clamping this foot to the inside of the cup rim.

The central spring 19 is a disk of resilient metal having a central opening through which the shaft 11 passes, and having a series of recesses 20 in its periphery and being concave out toward the adjacent part 17 of the connector 16; the peripheral sections left between the recesses 20 acting as spring

arms uniformly distributed around the shaft 11.

The guide arm 21 is cylindrical, with the shaft 11 passing diametrically through it 5 near one end and having a set screw 22 threaded into this end at an inclination to the axis of the arm, so that the screw 22 presents its slotted head for access of a screw-driver inserted over the rim of the 10 cup 5, for tightening this screw against the shaft 11, thereby clamping the arm 21 firmly on the shaft. The contact element 23 comprises the convex head 24 and a stem 25 fitting slidably in a bore in the outer end 15 of the guide arm 21, with a small coil spring 26 confined by the end of this stem, against the end of the bore; the spring 26 thus forcing the element 23 out so that its rounded head 24 bears against the inner stretches 20 of the coils of the wires 2 and 3 as the arm 21 is swung around by turning the knob 15.

Preferably, the connection of the two wires 2 and 3 is made as indicated in Fig. 3, a hole 27 being made in the core 1, and the 25 ends of the two wires 2 and 3 being passed inward through this hole, then around the edges of the core 1 around which they respectively just previously passed, bringing both ends of the wires to the outside, where 30 they are twisted together as at 28; the twisted together ends then being bent down alongside the core, between the adjacent stretches of wire, where they will be confined by the rim of the cup 5 when the parts 35 are assembled as before described.

By having the wires 2 and 3 of the same cross-section, or approximately the same, the device operates more uniformly, mechanically, and has a neater appearance, than if 40 there were a considerable difference in sizes of the wires to obtain a decided difference in rate of resistance increase per turn of wire traversed by the contact element 23, which rate, in the two wires 2 and 3, in the 45 present device, is provided by utilizing a different metal or alloy for each wire 1 and 2. As shown, the first wire 2 is considerably shorter than the second wire 3, in accordance with requirements for use with 50 two different kinds of vacuum tubes; the first wire 2 being sufficient for a tube of relatively low resistance, in proportion to which a comparatively short length of wire of low specific resistance affords ample variation, and all that is necessary, if a tube of 55 relatively high resistance is substituted, is to advance the contact element 23 over onto the second wire 3 as far as may be needed, to increase the resistance at a more rapid 60 rate, in proportion to the high resistance of the substituted tube.

Modifications of the construction, or of the proportions, as of the lengths of the

wires, may occur; and it will be seen that more than two wires may be combined, each 65 having a different specific resistance, if desired. Other modifications may occur, and therefore I do not wish to be understood as being limited to the precise example herein disclosed, but having thus fully described 70 my invention, what I claim as new and desire to secure by Letters Patent is:

1. In a rheostat, a curved supporting core, a plurality of resistance wires coiled around 75 said core, connected in series, one of said wires being of specific resistance different from that of another one of said wires, and a movable contact element making direct contact with successive coils of said wires.

2. In a rheostat, a curved supporting core, 80 a plurality of resistance wires coiled around said core, having adjacent end parts inserted through said core and secured together at the outer or convex side of said core whereby said wires are connected in 85 series, one of said wires being of specific resistance different from that of another one of said wires, and a movable contact element making direct contact with successive coils 90 of said wires along the inner or concave side of said core.

3. In a rheostat, a curved supporting core, a plurality of resistance wires coiled around 95 said core, having adjacent end parts inserted inward through said core and then passed around opposite edges of said core and secured together at the outer or convex side of said core whereby said wires are connected in series, one of said wires being of 100 specific resistance different from that of another one of said wires, and a movable contact element making direct contact with successive coils of said wires along the inner or concave side of said core.

4. In a rheostat, a plurality of resistance 105 elements stationarily connected in series, one of said elements being of specific resistance different from that of another one of said elements, and movable means for including various proportions of said one of said elements in a circuit, or all of said element and various proportions of said other element in the circuit.

5. In a rheostat, a plurality of resistance 115 elements stationarily connected in series, one of said elements being of specific resistance different from that of another one of said elements, but both of these elements being of substantially equal cross-sectional area, and movable means for including various proportions of said one of said elements in a circuit, or all of said element and various proportions of said other element in the 120 circuit.
